UNITED STATES PATENT OFFICE

ADOLPH L. NELSON, OF DETROIT, MICHIGAN, ASSIGNOR TO BOHN ALUMINUM & BRASS CORPORATION, OF DETROIT, MICHIGAN

PISTON

Continuation in part of application Serial No. 125,389, filed July 28, 1926. This application filed March 16, 1927. Serial No. 175,646.

This invention relates to pistons, particularly to pistons for use in internal combustion engines, and aims to improve the construction and operative results of such 5 pistons.

I have previously disclosed in my Patent No. 1,438,132 granted December 5, 1922, the use of relatively inexpandable struts to overcome the difficulties due to the high rate of 10 thermal expansion of certain light-weight piston materials, such as aluminum alloys. The present invention aims to utilize the principles heretofore disclosed and to produce an improved piston by the cooperation 15 of certain novel features of construction hereinafter more fully set forth.

The present application is in part a continuation of my application Serial No. 125,389 filed July 28, 1926.

20 In the drawings, Fig. 1 is an elevation partly in section of a piston embodying the invention;

Fig. 2 is a section on line 2—2 of Fig. 1;

Fig. 3 is a section on line 3—3 of Fig. 1;

25 Fig. 4 is a section on line 4—4 of Fig. 3;

Fig. 5 is an enlarged sectional detail showing a modified form of joint between the end of the strut and the bearing portions;

30 Fig. 6 is a view similar to Fig. 5 showing a further modification.

Referring to the drawings more specifically, the piston, which is preferably formed of light-weight material, such as an alloy of aluminum, comprises a head portion and a 35 skirt portion, the latter term applying to the zone lying below the head.

The piers 10, which depend from the head, are reinforced internally by ribs 11 and externally by a rib 12, and have the piston pin

40 bosses 13 formed therein. Below the pin bosses the piers connect with the horizontal arcuate webs 14, which are joined to the lower circular part 15 of the skirt. On opposite sides of the skirt and located 90° from the pin bosses, the semi-cylindrical bearing portions 16 and 17 extend upwardly from the circular part 15 of the skirt. These bearing portions 45 are discontinuous from the head and from the upper part of the piers and have homogeneous connections with the piers through

the ring 15 and webs 14. The circular portion 15 is reinforced at points directly below the opening 20 which lie between the piers and the bearing portions. This reinforcing may be accomplished in any convenient manner as by thickening the skirt at these points to form the pads 21.

Piston ring grooves 18 are cut into the side of the piston head, the lowest groove being positioned so that the slots 19, between 55 the bearing portions 16 and 17 and the head, are located at the bottom of this groove.

The skirt is provided with a slot or slots 60 extending upwardly from the lower end thereof as at 22.

A pair of flat, plate-like struts 24 extend between the bearing portions, the struts being located above the axis of the piston pin bosses and having their intermediate portions embedded in the material of the piers. 70 Positioning holes 25, formed in the strut, form means by which the strut is accurately positioned and positively held against all movement during the operation of casting. Additional apertures 26 are formed in the 75 strut and the material of the pier is permitted to flow through these apertures to strengthen and solidify the pier and assist in holding the strut in position.

The ends of the struts are formed with an 80 elongated dome-like structure 27 as clearly shown in Figs. 3 and 4. In casting the piston about the struts the dome ends 27 are permitted to form sockets in the bearing portions, but the material of the bearing portions 85 cannot grip the ends of the struts, and hence there is no positive connection between the struts and the bearing portions, but only a free surface contact.

By this construction the strut is positively 90 held by the material of the pier, the ends of the strut being merely propped against the bearing portions. This free joint between the struts and bearing portions reduces the 95 amount of heat transmitted through the piers and struts to the bearing portions.

As the piston cools after casting the bearing portions tend to contract toward each other, but the struts hold them out in positions 100 designed to give a certain clearance that will

prevent piston slap when the motor is cold, thereby setting up certain stresses in the bearing portions. As the piston warms up during operation the increase in temperature tends to relieve the stresses, but does not cause the bearing portions to expand away from the struts, as the operating temperatures are never as high as the casting temperature.

Obviously any suitable joint may be used between the strut end and the bearing portions, the desired result being a joint in which the bearing portion is merely propped against the end of the strut. In the joint of Fig. 6 the end of the strut is left straight and merely buts against the end of the bearing portions, while in Fig. 5 the end of the strut is bent to form an L-shaped foot 28.

It will be clear from Fig. 3 that the center of the joint between the end of the strut and the bearing portion is on the line $a-b$, and that the lines $a-b$ are closer together than the lines $c-d$, the center lines of the struts. This construction permits keeping the main parts of the struts spread far enough to suit certain piston designs, and at the same time reduces the effective length of aluminum between the ends of the struts, thereby reducing the amount of aluminum expansion that has a bearing on the resultant skirt expansion.

30 I claim:—

1. A piston comprising a head, sections depending from the head and having piston pin bosses secured thereto, bearing portions formed of light-weight material, and a pair of struts of material less expandible than the material of the bearing portions, the intermediate portion of each strut being embedded in a boss-carrying section, the ends of the strut having free surface contact with the bearing portions.

2. A piston comprising a head, sections depending from the head and having piston pin bosses secured thereto, bearing portions formed of light-weight material, a pair of struts of material less expandible than the material of the bearing portions, the intermediate portion of each strut being embedded in a boss-carrying section, the ends of the strut having free surface contact with the bearing portions, there being a connection between the bearing portions and the depending sections in addition to the struts, said connection being designed to carry the bearing portions.

3. A piston comprising a head, sections depending from the head and having piston pin bosses secured thereto, bearing portions formed of light-weight material, a pair of struts of material less expandible than the material of the bearing portions, the intermediate portion of each strut being embedded in a boss-carrying section, the ends of the strut having free surface contact with the bearing portions, the struts being located in the vertical zones of the piston pin bosses.

65 4. A piston comprising a head, sections de-

pending from the head and having piston pin bosses secured thereto, bearing portions formed of light-weight material, a pair of struts of material less expandible than the material of the bearing portions, the intermediate portion of each strut being embedded in a boss-carrying section, the ends of the strut having free surface contact with the bearing portions, the struts being located in the vertical zones of the piston pin bosses and there being a connection between the bearing portions and the depending sections in addition to the struts, said connection being designed to carry the bearing portions.

5. A piston comprising a head, sections depending from the head and having piston pin bosses secured thereto, bearing portions formed of light-weight material, and a pair of flat, plate-like struts of material less expandible than the material of the bearing portions, the intermediate portion of each strut being embedded in a boss-carrying section, the ends of the strut having free surface contact with the bearing portions.

6. A piston comprising a head, sections depending from the head and having piston pin bosses secured thereto, bearing portions formed of light-weight material, a pair of flat, plate-like struts of material less expandible than the material of the bearing portions, the intermediate portion of each strut being embedded in a boss-carrying section, the ends of the strut having free surface contact with the bearing portion, there being a connection between the bearing portions and the depending sections in addition to the struts, said connection being designed to carry the bearing portions.

7. A piston comprising a head, sections depending from the head and having piston pin bosses secured thereto, bearing portions formed of light-weight material, a pair of flat, plate-like struts of material less expandible than the material of the bearing portions, the intermediate portion of each strut being embedded in a boss-carrying section, the ends of the strut having free surface contact with the bearing portions, the struts being located in the vertical zones of the piston pin bosses.

8. A piston comprising a head, sections depending from the head and having piston pin bosses secured thereto, bearing portions formed of light-weight material, a pair of flat, plate-like struts of material less expandible than the material of the bearing portions, the intermediate portion of each strut being embedded in a boss-carrying section, the ends of the strut having free surface contact with the bearing portions, the struts being located in the vertical zones of the piston pin bosses and there being a connection between the bearing portions and the depending sections in addition to the struts, said connection being designed to carry the bearing portions.

9. A piston comprising a head, piers depending from the head, piston pin bosses formed in the piers, bearing portions formed of light-weight material, a pair of flat, plate-like struts of material less expansible than the material of the bearing portions, the intermediate portion of each strut being embedded in a pier, the ends of the struts having free contact with the bearing portions, and there being a connection between each bearing portion and each pier in addition to the struts, said connection being designed to carry the bearing portions. 70
10. A piston comprising a head, piers depending from the head, piston pin bosses formed in the piers, bearing portions formed of light-weight material, a pair of flat, plate-like struts of material less expansible than the material of the bearing portions, the intermediate portion of each strut being embedded in a pier, the ends of the struts having free contact with the bearing portions, the struts being located in the vertical planes of the piston pin bosses, and there being a connection between each bearing portion and each pier in addition to the struts, said connection being designed to carry the bearing portions. 75
11. A piston comprising a head, piers depending from the head, piston pin bosses formed in the piers, bearing portions formed of light-weight material, and a pair of flat, plate-like struts of material less expansible than the material of the bearing portions, each strut extending between the bearing portions and having its intermediate portion embedded in the material of a pier, the intermediate portion of the strut being formed with an aperture, the material of the pier 80
- extending through the aperture. 85
12. A piston comprising a head, sections depending from the head and having piston pin bosses secured thereto, bearing portions formed of light-weight material, and a pair of struts of material less expansible than the material of the bearing portions extending between the bearing portions, the centers of contact of the struts with a bearing portion being closer together than the longitudinal 90
- centers of the struts. 95
13. A piston comprising a head, a pair of struts of relatively inexpandable material, a cylinder bearing portion having a cast-in joint with an end of each strut, the centers 100
- of the cast-in joints being closer together than the longitudinal centers of the intermediate portion of the struts. 105
14. A piston comprising a head, piers depending from the head, piston pin bosses formed in the piers, bearing portions formed of light-weight material, and a pair of flat, plate-like struts of material less expansible than the material of the bearing portions, each strut extending between the bearing 110
- portions and having its intermediate portion
